TRANSDUCER

Howard W. Ashton, South Ardmore, Pa., assignor
to O. W. Storey & Associates, Chicago, Ill., a
partnership

Application April 9, 1947, Serial No. 740,419

7 Claims. (Cl. 171—330)

1

This invention relates to a transducer utilizing a capillary electrometer as the transducer element. In Patent 2,416,978 to Burgess, a capillary electrometer-type of transducer is disclosed. The invention herein is an improvement upon the invention disclosed and claimed in the Burgess patent and provides a simple, compact and efficient structure.

As disclosed in said Burgess patent, a capillary electrometer-type transducer comprises an insulating tube of glass or the like having a capillary channel within which mercury and an electrolyte, such as dilute sulphuric acid, meet forming at least one interface. Instead of mercury, gallium may be used and, instead of sulphuric acid, other solutions, organic or inorganic, may be used.

In order to provide effective transducer action, suitable means are necessary for transmitting energy to or from the capillary electrometer, depending upon the direction of energy conversion. The transfer of electrical energy from within the capillary system is comparatively simple and may, for example, be accomplished by the use of wire leads in conducting relation to the interface-forming liquids. The conduction of vibratory energy to or from the capillary system involves substantial difficulties. The invention addresses itself to means for providing a path for transfer of energy between the interior of the capillary electrometer and the exterior thereof. In general, the energy transfer path permits the flow of energy in either direction so that the transducer may be used either to convert electrical energy into mechanical energy or vice versa. While certain embodiments of the invention may be more advantageously used for conversion of energy in one direction, such as from mechanical energy to electrical energy, it will be understood, however, that the structures in general are reversible as far as operation is concerned.

A capillary electrometer has been found to be sensitive to liquid movement in connection with elastic deformation of an end wall-forming part of the enclosure for the interface-forming liquids. In order to utilize this mode of operation, this invention provides structures having weakened flexing portions to promote transfer of energy between the interior and exterior of the capillary system.

A more complete explanation of the principles of operation of structures embodying this invention is more conveniently given in connection with a description of the invention. The invention will, therefore, be described in connection with

2

the drawings wherein Figure 1 is a sectional elevation of a structure embodying the invention. Figure 2 is a sectional elevation of a modified form of structure embodying the invention. Figure 2A is a detail of the stylus mounting. Figure 3 is a sectional view of a modification of the structure shown in Figure 1. Figures 4 and 5 are sectional views of still further modifications.

Referring now to Figure 1, glass tube 10 has capillary channel 11 therein terminating in enlarged regions or chambers 12 and 13. Region 13 is connected by capillary bore 14 to gas chamber 15. Tube 10 has sealed end 16 in which is disposed wire lead 17. Wire lead 17 is sealed at 16 and extends through chamber 15. Lead 17 has portion 18 in coiled form extending through capillary 14 and into region 13. Portion 18 of the wire may be of platinum or other conductor inert to the interface-forming liquids. Wire 17 itself 20 may be of cheaper material, such as borated copper, and may be heavy enough to permit handling.

Disposed within enlarged regions 12 and 13 are bodies of mercury. Within capillary 11 are globules of mercury and other interface-forming electrolyte, such as sulphuric acid diluted to a concentration of the order of between 10 and 40%. Inasmuch as the requirements for liquids forming a capillary electrometer system are well known, it is unnecessary to go into detail. Chamber 15 has gas or air therein at any desired pressure. Inasmuch as the gas pressure in chamber 15 provides compliance to the system, the characteristics of the system may be controlled by 35 choice of gas pressure.

Capillary bore 11 may have a diameter of between about five and about one hundred microns (.005 mm. to .1 mm.) and may have any desired length, such as, for example, 10 mm. although other bore diameters and lengths may be used. Enlarged regions 12 and 13 may themselves be of capillary dimensions, such as about one mm. in diameter and may have a length of about 5 mm. It is understood that capillary bore 11 and enlarged regions 12 and 13 are circular although other cross-sectional configurations may be used. In general, region or chamber 13 should have as small a volume as possible consistent with good construction.

Sealed in the wall of glass tube 10 is lead 20 having portion 21 extending within region 12. If desired, auxiliary glass portion 22 may be utilized for forming chamber 23 within which the 55 junction of wire 20 and tip 21 may be disposed.

Thus, if tip 21 is a fine piece of platinum, wire 20, like wire 11, may be of heavy borated copper.

Tube 10, adjacent region 12, flares to provide annular portion 25. This portion may have substantial thickness and rigidity. Carried by portion 25 at the edge thereof is diaphragm 27, the diaphragm being joined to portion 28 at annular flexing region 28. Diaphragm 27 is most conveniently formed of glass and is fused to portion 25. Annular flexing region 28, where the two portions unite, is thin and has substantial flexibility. It is preferred to have diaphragm 27 quite rigid, although this may be thin and flexible if desired.

Region 30 within annular portion 28 and between diaphragm 27 and portion 25 is filled with liquid, such as mercury. If desired, a gas chamber similar to 15 may be provided in communication with regions 12 or 30. It is understood that the capillary passage leading to a gas chamber, such as passage 14 for example, are fine enough to prevent liquid, such as mercury, from passing through.

The structure so far described in Figure 1 may be used as a capillary microphone. Sound waves in air or in liquid impinging on the outside of diaphragm 27 will cause displacement of the interfaces in capillary bore 11 and result in potentials being generated by the electrometer. It is not necessary that portion 25 flare as much as indicated in the drawing. It is desirable to have diaphragm 27 and flaring portion 25 spaced quite close to reduce the volume of region 30. It is only necessary that diaphragm 27 have sufficient space within which to vibrate freely without touching flaring portion 25.

It is evident that, in the construction shown in Figure 1, a substantially incompressible connection is provided between diaphragm or piston 27 and the interfaces within capillary bore 11. This is true even though small bubbles of gas may be permitted to remain within the system. In view of the nature of this connection and the fact that the energy is transmitted by compressional waves in the liquid, it is clear that the liquid path itself need not necessarily be straight. It is desirable to so design the liquid path that interference and diffraction effects are avoided. However, it is evident that the comparatively narrow liquid path provided by regions 12 or 13 in Figure 1 may be bent out of a straight line without having substantial effect on the transmission characteristics of the liquid path.

Referring, therefore, to Figure 2, a modified construction is shown wherein glass tube 10' has portion 35 bent as shown to form a substantial right angle. This is exemplary and the amount of bend may be set to any desired value. Beyond bend 35, glass tube 10' has portion 36 terminating in annular flexing region 37. Region 37 may be constructed generally along the same lines as the corresponding part in Figure 1 with a comparatively heavy flaring portion 38. This construction, however, differs from Figure 1 in that part 39 of the annular portion is reinforced. Heavy wall portion 40 is provided. Wall portion 40 carries rod 41 of glass or other suitable material. Flat spring 42 extends from rod 41 and has attached thereto stylus tip 43. Stylus tip 43 may be of the type used in phonograph work and may conveniently be formed of a sapphire or other jewel or of hard metal, such as carballoy, tool steel, or the like. Spring 42 is flexible for vertical stylus movement but quite rigid for lateral stylus movement.

In order to protect the transducer or pick-up from damage due to careless handling, hood 45 may be disposed around the same. Hood 45 may be of plastic or sheet metal or any other suitable material and has a generally conical shape. The hood may be formed in two portions and may be cemented around part 36 of the glass tube. Hood 45 has tapered portion 46 which approaches stylus tip 43 and provides just enough clearance for proper stylus operation. In the event that the structure is dropped upon the stylus tip, weakened region 37 will yield sufficiently to permit the tapered portion of the hood to take up the shock and prevent excessive flexure of the glass.

The entire pick-up may be rigidly supported by suitable means clamping the body of tube 10' and may be disposed in a tone arm in a conventional manner.

In the transducer shown in Figure 2, wall 40 is adapted to be tilted rather than moved like a piston, as in Figure 1. Transverse movement of stylus tip 43 will cause tilting of wall 40 with respect to reenforced portion 39 and result in transducer action. This is due to the fact that reinforcement 39 does not extend all the way around annular region 37 but forms only a small part thereof. It is, thus, evident that reenforced portion 39 of annular region 37 should be properly oriented. Vertical movement of the stylus will be dissipated in spring 42, while lateral movement will be effective for transducer operation.

Referring now to Figure 3, the transducer is generally similar to that shown in Figure 1 except that tube 10 has flaring portion 50 in the general shape of a conical surface. Portion 50 has thin flexing region 51, and this region supports concave vibratory portion 52. Conical portion 50 may have a shape similar to a portion of a spherical surface rather than a cone. Such a construction may be formed from a hollow glass sphere by softening the glass and pressing the same against a suitable die member.

In Figure 4, a somewhat modified construction is shown wherein flaring portion 53 has flexing portion 54 and has concave portion 55 of the shape shown. As clearly indicated in the drawing, this concave vibratory portion has the general shape of a saucer.

In Figure 5, a construction similar to Figure 4 is shown but differing therefrom in that lead 57 passes through the concave vibratory portion 55'. Lead 57 may be made rigid enough to function not only as an electric conductor but also as a mechanical element. Thus, forces transverse to lead 57 or along the length of lead 57 may be provided for operating on diaphragm portion 55'. It is understood that the forms shown in Figures 3 to 5, inclusive, are maintained rigidly in position by suitable means clamping the body of the transducer. It is also possible to rely upon inertia for maintaining the body of the transducer in more or less fixed position.

What is claimed is:

1. A transducer comprising a tubular insulating member having a capillary bore and enlarged regions at opposite ends of said bore, capillary electrometer interface-forming liquids within said member and forming at least one interface within said bore, conducting liquids in said regions, said tubular member having a flaring portion at one end thereof and having an end wall sealing said tubular member at the flared portion, said flaring portion forming part of one of said enlarged re-

gions and having a weakened, annular flexing zone, and leads to the liquids on opposite sides of the capillary.

2. The structure according to claim 1 wherein said insulating member is sealed and is formed of glass.

3. The structure according to claim 1 wherein said insulating member is sealed and the liquid bodies on opposite sides of the capillary are mercury.

4. The structure according to claim 1 wherein said end wall is substantially flat.

5. The structure according to claim 1 wherein said end wall is concave.

6. The structure according to claim 1 wherein a gas chamber is provided in communication with said tubular glass member.

7. A transducer comprising a sealed tubular glass member having a capillary bore at an intermediate point thereof and enlarged regions at opposite ends of said bore, mercury and sulphuric acid within said capillary bore and forming at

least one interface within said bore, mercury in said enlarged regions for providing electrically-conducting paths to said interface-forming liquids, said tubular member having a flared portion at one end thereof and having an end wall sealing said flared portion with a weakened annular flexing zone at said flared portion for permitting vibration of said end wall, said end wall and flared portion forming part of one of the liquid-filled regions, leads to the liquids in said two regions, said end wall being adapted to vibrate during energy conversion.
